Primary Examiner — Natasha Vujcic*(74) Attorney, Agent, or Firm* — Simon Kuang Lu(57) **CLAIM**

The ornamental design for an LED suspension luminaire as shown and described.

DESCRIPTION

FIG. 1 is a front, perspective view of an LED suspension luminaire showing our new design;
FIG. 2 is a front view of an LED suspension luminaire;
FIG. 3 is a rear view of an LED suspension luminaire;
FIG. 4 is a left side view of an LED suspension luminaire;
FIG. 5 is a right side view of an LED suspension luminaire;
FIG. 6 is a top plan view of an LED suspension luminaire;
FIG. 7 is a bottom plan view of an LED suspension luminaire;
FIG. 8 is a bottom, perspective view of the LED suspension luminaire shown in a position of use; and,
FIG. 9 is a top, perspective view of the LED suspension luminaire shown in a position of use.

The broken lines in the drawings illustrate the environment of the LED suspension luminaire which forms no part of the claimed design.
